(57) **CLAIM**

The ornamental design for a utensil, as shown and described.

DESCRIPTION

FIG. 1 is a front perspective view of the utensil showing the new design;

FIG. 2 is a rear perspective view thereof;

FIG. 3 is a front elevation view thereof;

FIG. 4 is a rear elevation view thereof;

FIG. 5 is a left elevation view thereof;

FIG. 6 is a right elevation view thereof;

FIG. 7 is a top plan view thereof;

FIG. 8 is a bottom plan view thereof;

FIG. 9 is a front perspective view of the utensil of FIG. 1 in a second position of use wherein the knife is deployed;

FIG. 10 is a rear perspective view thereof;

FIG. 11 is a front elevation view thereof;

FIG. 12 is a rear elevation view thereof;

FIG. 13 is a left elevation view thereof;

FIG. 14 is a right elevation view thereof;

FIG. 15 is a top plan view thereof;

FIG. 16 is a bottom plan view thereof;

FIG. 17 is an exploded front perspective view of the utensil of FIG. 1 in a third position of use wherein the knife is deployed and the fork is removed from the spoon and knife sub-assembly;

FIG. 18 is an exploded rear perspective view thereof;

FIG. 19 is an exploded front elevation view thereof;

FIG. 20 is an exploded rear elevation view thereof;

FIG. 21 is an exploded left elevation view thereof;

FIG. 22 is an exploded right elevation view thereof;

FIG. 23 is an exploded top plan view thereof; and,

FIG. 24 is an exploded bottom plan view thereof.

1 Claim, 16 Drawing Sheets
